UNITED STATES PATENT OFFICE

2,128,586

FIREWORKS

Joseph Haslun, Yonkers, N. Y.

Application November 25, 1936, Serial No. 112,651

7 Claims. (Cl. 102—23)

This invention relates to fireworks and more particularly to skyrocket constructions.

Among the objects of the invention is to generally improve the construction of skyrockets and like types of fireworks which shall comprise few and simple parts which are easily assembled to form an attractively appearing structure, which shall be cheap to manufacture, and which shall be efficient and practical to a high degree in use.

Other objects of this invention will in part be obvious and in part hereinafter pointed out.

The invention accordingly consists in the features of construction, combination of elements and arrangement of parts which will be exemplified in the construction hereinafter described and of which the scope of application will be indicated in the following claims.

In the accompanying drawing in which is shown one of the possible illustrative embodiments of this invention,

Figure 1 is a front elevational view of a skyrocket construction embodying the invention.

Figures 2 and 3 are enlarged cross sectional views taken on lines 2—2 and 3—3 in Figure 1.

Figure 4 is a cross sectional view corresponding to a cut taken on line 4—4 in Figure 2, and

Figures 5, 6 and 7 are front elevational views of the separated parts of the skyrocket, namely, the cap, outer casing and shell, respectively, shown disassembled, said cap and casing being shown collapsed for shipment or storage.

Referring in detail to the drawing, 10 denotes a skyrocket type of firework constructed to embody the invention. Said skyrocket 10 is seen from Figure 3, to comprise a cylindrical type of shell 11 which may be filled with a usual propelling charge C in the lower end 11a thereof and also may contain an explosive and colored illuminating display material (not shown) in the head end 11b. Said shell 11 and contents may be assembled in any suitable manner well known in the art.

The charge C is retained in the shell end 11a by a suitable plug closure 12 which is provided with an axial passage 12a through which a cord fuse 13 is inserted, a folded end 13a thereof extending into the charge C. A free end 13b of said fuse 13 projects beyond the shell end 11a for setting off the skyrocket.

The novel construction embodying the invention will now be described. Applied over the filled shell 11 there is provided a casing 14 made of suitable sheet material, such as cardboard or the like. Said casing 14 preferably comprises a tapered tubular structure which may be collapsed

for shipping or storage before assembly, as shown in Figure 6, and as here shown when applied over the shell is of hexagonal cross section. See Figure 2.

Said casing 14 has its lower end 14a sized to circumscribe the circular shape of the shell end 11a which snugly fits therein. The other or upper end 14b of the casing 14 may be made with flaps 14c which are adapted to be bent inwardly toward the upper end 11b of shell 11, said flaps 14c being so cut and shaped to slopingly embrace with the free edge 14d of the shell end 11b, as shown in Figures 3 and 6. Said flap edges 14d may be secured to the shell end 11b by a suitable adhesive 15. As a top cover on the upper or leading end of the skyrocket 10, a cap 16 is provided. Said cap 16 preferably is made of a sheet material similar to that of the casing 14 and before assembly can be collapsed as shown in Figure 5.

The cap 16 may be attached to the upper end 20 of the casing 14 with the shell end 11b fitted therein by suitable adhesive means 15a which also secures the flap edges 14d to the shell end 11b, the outer surfaces of the flaps 14c serving as a seat for the cap 16 as shown in Figure 3.

Extending up along the casing 14 from the lower end 14a thereof, a slot 17 is provided, said slot 17 being of sufficient width to receive the usual stick 18 which may be of square cross section. As shown in Figure 3, the upper end of the stick 30 18 may be grooved as at 18a to engage with the inner edge portion of the slot 17. The side edges of said slot 17 abutting the stick 18 serves to retain the stick 18 against side movement with respect to the shell 11, as seen from Figure 3.

To fixedly secure the stick 18 in its assembled position, a binding wire 19, extending about the stick 18 and lower casing end 14b, is provided. See Figures 1, 2 and 3.

An additional novel feature of construction in 40 the assembly of the fuse 13 in the filled shell is provided in having a member 20 extending from the lower casing end 14b. Said member 20 has an elongated opening 20a in the mid-portion thereof which is just large enough to permit the 45 passage of the folded cord fuse 13, said opening 20a being located to register with the axial passage 12a when the member 20 is positioned to extend over said bottom of the shell and 11a, as shown in Figures 3 and 4. The free end 20b 50 of the member 20 may be inserted between the lower casing end 14a and the shell end 11b to retain said member 20 in effective position shown in Figure 4.

The fuse 13 when inserted into the opening 20a 55

and through the passage 12a has a short end 13a of the folded portion thereof within the opening 20a spring out of alignment with respect to the latter to act as a detent or stop against falling 5 or being pulled out of the assembled position shown in Figure 3.

In practicing the invention, skyrocket 10 may be shipped "knocked down" that is, the filled shell 11, casing 14, cap 16 and stick 18 may be separated for convenience and economy in packaging, shipping and storage. To assemble the skyrocket 10, the filled shells 11 are inserted in the casings 14 with the upper ends 11a of the shells coinciding with the curved edges 14d of the flaps 15 14c. By then dipping the upper shell ends 11b into an adhesive supply for securing the edges 14d of the flaps 14c thereto, the outer surfaces of said flaps 14c are simultaneously coated with the adhesive 15a. The cap 16 is then applied in position. Said flaps 14c are thus made to serve as efficient seating means for retaining the caps 16.

The sticks 18 may next be inserted into the slots 17 and the binder wire 19 clamped in place, as shown in Figures 1, 2 and 3.

The cord fuse 13 may then be inserted into the openings 20a of the member 20, the latter being previously secured to extend across the bottom end of the shell 11a and casing 14a. The fuse 13 is preferably made of a stiff, yet resilient material and an end 13a thereof folded over on itself so that the folded portion 13a thereof is sufficiently long to extend well into the charge C. The short end 13b of the folded portion 13a, after entering the opening 20a will spring slightly out 35 of alignment with respect to said opening 20a and will abut said member 20, as shown in Figures 2, 3 and 4. The skyrocket 10 will now be ready for use in the well understood manner.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention I claim as new and desire to secure by Letters Patent:

1. In fireworks construction of the character described, a shell filled with combustible illuminating material having an ignition fuse carried by one end, a casing fitted to extend over the entire shell, means for securing a portion of the casing to the shell, and a hollow, tapered cap seated on an end of the casing and shell opposite said ignition fused end.

2. A housing for a fireworks element comprising a casing, flaps extending from one end of said casing for securing the latter to the element, and

a member extending from the other end of said casing having an opening, said member and opening forming a fuse retaining means.

3. A housing for a fireworks element comprising a casing, flaps extending from one end of said casing for securing the latter to the element, said casing having a stick receiving slot extending along a side thereof at a spaced distance from the flaps.

4. In combination with a cylindrical shell filled with combustible illuminating material, a tubular casing fitted to extend over the entire shell, flap end portions extending from said casing, said flap end portions being constructed and arranged to conform to the shape and size of an end of the shell, adhesive means for securing said flap end portions to the shell, and a cap seated on said flap end portions and secured to said casing to terminate said casing and shell.

5. A tapered shaped tubular casing adapted to be collapsed when not in use and adapted to house a firework element, said casing being substantially the length of the firework element, the end of said casing of largest cross sectional area having flap extension portions for attaching to said element, the end of said casing of smallest cross sectional area being sized to snugly fit said element, said flap extension portion end when attached to said element forming a seat tapered relatively opposite to that of the casing, and a cap adapted to be adhesively secured on the seat.

6. A tapered shaped tubular firework receiving member comprising a casing adapted to be collapsed when not in use and adapted to house a firework element and a pyramidal cap therefor, said casing being shorter than the firework element, the end of said casing of largest cross-sectional area having flap extension portions for attachment of said cap thereto, the end of said casing of smallest cross-sectional area being sized to snugly fit said element, the upper portion of the member cooperating with the element to hold the same, said end of the casing of smallest cross-sectional area being provided with a slot adapted to receive a stick support for said element.

7. A tapered shaped tubular firework receiving member comprising a casing adapted to be collapsed when not in use and adapted to house a firework element and a pyramidal cap therefor, said casing being shorter than the firework element, the end of said casing of largest cross-sectional area having flap extension portions for attachment of said cap thereto, the end of said casing of smallest cross-sectional area being sized to snugly fit said element, the upper portion of the member cooperating with the element to hold the same, and a tab having an opening therein, said tab extending from said end of said casing of smallest cross-sectional area and forming a fuse retaining means for a fuse of said firework element.

JOSEPH HASLUN.
